DESIGN FOR A COMBINED HOT AIR SHIELD AND FILTER

Joseph R. Barclay, Muncie, Ind.

Application January 17, 1941, Serial No. 98,162

Term of patent 3½ years

To all whom it may concern:

Be it known that I, Joseph R. Barclay, a citizen of the United States, and resident of Muncie, in the county of Delaware and State of Indiana, have invented a new, original, and ornamental Design for a Combined Hot Air Shield and Filter, of which the following is a specification, reference being had to the accompanying drawing, forming a part thereof.

The figure is a perspective view of a combined hot air shield and filter showing my new design, the other end of the article being substantially like the end shown.

I claim:

The ornamental design for a combined hot air shield and filter, as shown and described.

JOSEPH R. BARCLAY.
